OPERATING MECHANISMS FOR ELECTRIC SWITCHES

George J. Meuer, Milwaukee, Wis., assignor to Cutler-Hammer, Inc., Milwaukee, Wis., a corporation of Delaware

Application July 26, 1940, Serial No. 347,600

13 Claims. (Cl. 200—5)

This invention relates to improvements in operating mechanisms for electric switches.

A primary object of the invention is to provide novel mechanical interlocking means for the operating elements of a plurality of electric switches, whereby operation of each of said switches to complete its associated circuit is prevented pending operation of another of the switches to interrupt its associated circuit.

Another object is to provide a switch mechanism of the aforementioned character involving use of two electric switches each of which is normally biased to its "off" position.

Another object is to provide such a switch mechanism having operating elements of the pushbutton type.

Another object is to provide novel means for mounting and enclosing a switch mechanism of the aforementioned character, to afford a unitary control station of the pendant pushbutton type.

Another object is to provide such an interlocked pushbutton control station enabling use of a pair of like switches most of the elements of which may be of standard construction.

Another object is to provide a pendant pushbutton control station of the aforementioned character adapted for control of either direct current or alternating current circuits, depending upon the particular type of switches employed.

Another object is to provide a metal enclosing casing which is unequally divided longitudinally, the large section of said casing having means to facilitate attachment of the switch mechanism thereto as a unit and means to guide the respective operating elements of the switches.

Another object is to provide a novel form and arrangement of the switch terminals to facilitate attachment of the circuit wires after assembly of the switch mechanism with respect to the main section of the casing.

Another and more specific object is to provide a pendant pushbutton control station having a switch mechanism of the double-pole, double-throw type.

Another object is to provide novel means for grounding the metal enclosing casing.

Another object is to provide a pendant pushbutton control station wherein each pushbutton operating element is of the manual hold down type.

Another and more specific object is to provide a manual reversing station for control of a motor operated hoist or the like.

Other objects and advantages of the invention will hereinafter appear.

The accompanying drawings illustrate several embodiments of the invention which will now be described, it being understood that the embodiments illustrated are susceptible of modification in respect of certain structural details thereof without departing from the spirit of my invention or the scope of the appended claims.

10 In the drawings, Figure 1 is a side elevational view (full size) of a pair of mechanically united and mechanically interlocked switches forming the reversing switch mechanism, the metal enclosing casing being shown in central longitudinal section, the "on" position of one of the pushbuttons and its associated switch actuating element being shown in dotted lines.

Figure 2 is a bottom plan view of the pendant pushbutton control station illustrated in Fig. 1, the metal cover of the casing being removed.

Fig. 3 is a fragmentary view similar to Fig. 1, but with one switch shown in longitudinal section, and with its operating button depressed.

25 Fig. 4 is a side elevational view (full size) of a reversing switch mechanism of relatively greater current controlling capacity than that illustrated in Figs. 1 to 3, the pivoted lever providing the mechanical interlock between the switch operating elements being shown in section, and the two-part metal enclosing casing being shown in longitudinal section.

30 Fig. 5 is a top plan view of the switches assembled with respect to the supporting plate, which plate is adapted for releasable attachment to the large section of the enclosing casing.

35 Fig. 6 is a view in section of the casing, on the broken line 6—6 of Fig. 4, showing in elevation the end of the left-hand switch of Fig. 4, the operating pushbutton of said switch being shown depressed in full lines and in its normal position in dotted lines.

40 Fig. 7 is a detail perspective view of the mechanical interlocking lever of the switch mechanism, the biasing leaf spring being shown attached thereto.

45 Fig. 8 is a central longitudinal section through the large section of the casing and through one of the switches, illustrating another modified form of mechanical interlock for the pair of switches, the switches illustrated being particularly adapted for control of alternating current.

50 Fig. 9 is a top plan view of the supporting plate with the pair of switches attached thereto, showing the interlocking lever associated with the

pushbuttons and the biasing springs associated with said lever.

Fig. 10 is a sectional view, on the line 10—10 of Fig. 8.

Fig. 11 is a perspective view of the interlocking lever shown in Figs. 8 and 9, and

Fig. 12 is a fragmentary view, partly in section on the line 12—12 of Fig. 8, illustrating the means employed in each of the two switches for normally biasing the same to "off" position.

Referring first to the form of pendant pushbutton reversing station illustrated in Figs. 1 to 3, the numeral 15 designates the front or larger section of a cast metal enclosing casing, the smaller rear section or cover of said casing being designated by the numeral 16. The cast sections 15 and 16 of the casing are recessed, as best illustrated in Fig. 1, to provide a relatively thin-walled structure of adequate strength.

To provide for releasable attachment of the casing sections to each other, the section 15 is provided at four symmetrically arranged points with enlargements or posts 17, 18, 19 and 20 formed integrally with the side walls thereof, said posts being recessed, preferably by the casting operation, and tapped to receive the shanks of securing screws, two of which are shown in dotted lines at 21, 21 in Fig. 1. Section 16 is provided with four correspondingly arranged integral posts, two of which are shown at 22 and 23 in Fig. 1, the posts last mentioned being provided by the casting operation with openings providing clearance for the shanks of said screws 21. Also, as indicated by dotted lines in Fig. 1, section 16 is provided in its outer surface with countersinks to accommodate the heads of said screws 21.

Section 15 is provided in one end wall thereof with a circular opening 24 through which a conductor cord (not shown) may be inserted for attachment of the wires thereof to the respective switch terminals. In practice the portion of the end wall surrounding said opening 24 is made relatively thick to provide for attachment thereto of any well known form of metal cord grip or clamp (not shown) to provide a strain relief for the wires attached to the switch terminals. The conductor cord may, of course, be of the metal- or rubber-armored type to provide adequate support for the pushbutton station, which is preferably of the pendant type.

Section 15 is further provided on its opposite side walls with four symmetrically arranged posts 25, 26, 27 and 28 the flat faces of which form ledges located in a common plane offset inwardly from the edge 15^a at the open end of said section. Posts 25 to 28 are provided with recesses (not shown) which are tapped to receive the shanks of a corresponding number of screws 29, which serve to secure within said section a metal supporting plate 30 for the pair of switches employed. Section 15 is provided at longitudinally spaced points with two pairs of integral, laterally spaced ribs or struts 31, 32 and 33, 34, the adjacent opposed edges of which pairs of ribs act as guide surfaces for inverted channel-shaped metal members 35, 35 which are attached to the pushbuttons 36, 36 associated with the respective switches employed in the combination. The front wall 15^b of section 15 is provided with circular openings 15^c and 15^d to permit reciprocation of said pushbuttons.

In the device of Figs. 1 to 3 I have illustrated the use of a pair of like switches 37, 37 of the double-pole "on" and "off" snap action type, the particular switches employed having a current

controlling capacity of ten amperes direct current. Said switches are in general of the character disclosed and claimed in my Patent No. 1,889,259, dated November 29, 1932, and in my Patent No. 1,977,878, dated October 16, 1934, to which reference may be had for a more detailed explanation of the construction and mode of operation of such switches.

As indicated by the section in Fig. 3, each switch comprises essentially a molded insulating base having a recess opening to the upper end thereof, the bottom wall of the recess having a central rib upon the flat surface 37^a of which a flat insulating contactor-carrier 37^b is adapted to slide. Carrier 37^b has attached thereto, on opposite sides of said rib, a pair of contactors each having portions exposed on opposite faces of the carrier, one of the contactors being designated by the numeral 37^c.

Said contactors are adapted for movement thereof jointly into and out of bridging engagement with pairs of upper and lower resilient contacts, the upper contact of one pair being designated by numeral 37^d. The means for effecting snap movement of the contactors into and out of bridging engagement with the pairs of contacts comprises an insulating member 37^e having a lost motion driving connection with the walls of an opening 37^f in carrier 37^b; said member 37^e being pivotally supported by a U-shaped wire member or yoke 37^g, the opposite arms of which are pivotally engaged with openings provided in a boss 37^h formed on the metal top plate 37ⁱ, as shown at 37^k in the upper switch of Fig. 3. Each switch is provided with an insulating top plate 37^m.

A coiled compression spring 37^l is interposed between member 37^e and the end 38^a of a toggle lever 38, which is here shown as of special form. Thus lever 38 is pivoted by a pin 39 within a hollow bushing 40 which is rigidly and non-rotatably attached to boss 37^h in the manner indicated in Fig. 3. The upper, initially closed, end of bushing 40 is provided with a saw-cut or kerf in its top and sides (see Figs. 3 and 5) to provide clearance for the arms 38^b and 38^c of the lever 38 upon oscillatory movement of the latter.

Arm 38^c of said lever is provided with an opening 38^d of substantially elliptical form to accommodate a headed pin 41 the shank of which penetrates alined openings in the opposite side walls of member 35, the shank end of said pin being enlarged or upset, as shown at 41^a in Fig. 1, to retain the same in assembled relation.

The end of lever arm 38^b is formed as shown at 38^e, said end (in respect of the left-hand lever of Fig. 1 and the corresponding upper lever of Fig. 3) being primarily adapted for cooperation with member 35 of the other switch of the combination to provide a mechanical interlock between the two pushbuttons 36; so that either of the pushbuttons 36 may be depressed to an extent sufficient to effect closure of the contacts of its associated switch (as indicated by dotted lines in respect of one switch in Fig. 1, and as indicated in respect of the other switch in Fig. 3), but both pushbuttons may not be simultaneously depressed to an extent sufficient to effect closure of the contacts of both switches.

Thus as shown in dotted lines in Fig. 1 upon depression of the left-hand pushbutton 36 the end 38^e of the lever arm 38^b associated therewith is tilted or rotated in a counterclockwise direction into engagement with the horizontal portion of the member 35 associated with the other pushbutton, thus preventing manual depression of

the latter. Similarly, with reference to Fig. 3, upon depression of the lower pushbutton the member 35 is so positioned with respect to the end 38^a of the lever arm 38^b associated with the upper switch as to prevent depression of the upper pushbutton.

In practice the members 35 attached to the respective pushbuttons cooperate with the inner surface of the wall 15^b of section 15 to limit the extent of upward or outward movement of the pushbuttons with respect to the enclosing casing. However, the ends 38^a of the respective lever arms 38^b are adapted to abut against the supporting plate 30 to limit the extent of upward movement of the pushbuttons prior to assembly of the combined switch unit with respect to casing section 15, thus insuring maintenance of the various switch operating parts in assembled relation to plate 30.

The pushbuttons 36 are additionally guided, or limited to straight-line reciprocating movement, by a pair of like pins 42, 42, the flat ends of the conical head portions 42^a of which are adapted to seat against the flat insulating cover plates of the respective switches, the metal supporting plate 30 having a pair of properly spaced openings 30^a to accommodate portions of the heads 42^a, and the shanks of said pins extending to a plane substantially coincident with the inner surface of the wall 15^b of section 15. Each pushbutton 36 is provided with a recess 36^a of circular form in transverse cross section to provide for a relatively close sliding fit thereof with respect to the shank of pin 42. Each pushbutton 36 is also preferably provided with an integral extension 36^b (Fig. 3) of reduced size in transverse cross section, the arrangement being such that guiding of the pushbutton by its associated pin 42 is insured in all positions of the former.

Each pushbutton 36 is also biased to its outer extreme position, as by means of a coiled compression spring 43 which is interposed between supporting plate 30 and the upset flange 36^c which rigidly secures member 35 to its respective pushbutton. As shown in Fig. 3 each spring 43 surrounds its associated pin 42 and the reduced end portion 36^b of the pushbutton associated therewith, the expanded and compressed conditions of the respective springs 43 being illustrated.

Inasmuch as the switches 37 as initially constructed are of the end-wiring terminal type, I prefer to provide additional terminal members to provide for bottom-wiring of the switches after the same have been assembled with respect to casing section 15. Accordingly I omit the usual brass binding screws associated with the four end-wiring terminal members of each switch and position against each of said terminal members one end of an approximately L-shaped terminal member which is perforated to provide clearance for the shank of a steel screw 44 which acts to clamp said L-shaped member to the terminal. Lock washers 44^a are preferably associated with the heads of screws 44 to prevent accidental loosening of the latter. As best illustrated in Fig. 1, six of the auxiliary terminal members 45 are of like form and size, or thickness; whereas two of said auxiliary terminal members 46 are of relatively thinner stock and have perforated portions underlying the adjacent or middle terminals of the pair of switches. The free end portions of terminal members 45 are tapped to accommodate the shanks of the usual brass binding screws 47, six of which are required in the complete combination. Thus it will be apparent that

the two middle binding screws of the switch combination respectively provide a common electrical connection for one stationary contact of each switch. That is to say, upon depression of one pushbutton 36 the switch associated therewith is adapted to function to complete a given circuit (say, a hoist motor circuit for effecting operation thereof in one direction), whereas upon depression of the other pushbutton 36 (with a required release of the first pushbutton) a circuit will be completed for effecting reverse operation of the hoist motor (not shown).

In practice the section 15 of the casing is provided with an integral post or stud 48 having a binding screw 49 associated therewith and adapted for clamping engagement with a grounding wire (not shown) which may form a part of the conductor which enters through opening 24 in section 15 of the casing.

The form or contour and ornamentation (not shown herein) of the complete switch unit constitute the subject matter of my Design Patent 121,962, granted August 13, 1940, for Design for a pendant electric switch.

The modified form of device illustrated in Figs. 4 to 7 is in general quite similar to that of Figs. 1 to 3. The two double-pole, single throw snap switches 50, 50 employed in the device of Figs. 4 to 7, although of the character disclosed and claimed in my aforementioned Patents Nos. 1,889,259, and 1,977,078, are of substantially greater size than those of Figs. 1 to 3, the switches 50 preferably having a current controlling capacity of twenty amperes direct current. Because of the larger size of switches 50 the casing 51, 52 is, of course, correspondingly larger than the casing 15, 16 aforescribed. On the other hand, certain of the switch operating parts may be identical with those aforescribed and the same have been given corresponding numerals of reference. Thus, the pushbuttons 36, members 35, guide pins 42, springs 43, bushings 40 and pivot pins 39 and 41 may be structurally and functionally like those parts aforescribed.

Similarly the casing section 52 is provided with two transversely aligned pairs of guide ribs, one pair being shown at 53, 54 in Figs. 4 and 5, and one rib of the other pair being shown at 56 in Fig. 4, the spaced edges of which pairs of ribs cooperate with members 35 to assist in guiding the respective pushbuttons. Pushbuttons 36 are further guided by means of pins or studs 42, 42 and said pushbuttons are biased to the extreme positions thereof shown in Fig. 4 by the aforementioned springs 43. Pins 42 are associated with a metal support plate 57 to which the respective switches are attached as by means of pairs of screws or bolts certain of which are shown at 58 in Figs. 4 and 5.

Plate 57 is preferably of rectangular contour, as shown in Fig. 5, and is provided with four symmetrically arranged openings 57^a, 57^b, 57^c and 57^d to accommodate the shanks of a corresponding number of screws 59 (see Fig. 6) which take into tapped openings provided in posts, certain of which are shown at 51^a, 51^b, 51^c in Figs. 5 and 6, whereby said plate with its attached switches may be secured to section 51 of the casing. The operating means for the respective switches comprise bell crank levers 60, the arm 60^a of each lever being pivotally connected with one of the members 35 as by means of the pin 41, and the other arm 60^b (dotted lines, Fig. 4) cooperates with its associated switch parts to effect circuit completing and interrupting opera-

tion thereof with a snap action. As will be understood, the hollow metal bushings 40 may be identical with those aforescribed, the same having kerfs in the upper end thereof to accommodate the arms 60^b of levers 60, which are pivotally supported as by means of pins 39, and to provide clearance for the arms 60^a upon oscillation of the respective levers.

The means for providing a mechanical interlock between the pushbuttons 36 of the respective switches preferably comprises an interlock lever 61 the flat main body portion of which is pivotally attached to the support plate 57 as by means of the rivet stud 62, in the manner best illustrated in Fig. 4. Lever 61 is provided with end portions 61^a and 61^b of equal length bent upwardly at a right angle thereto, and portion 61^a has attached thereto, as by means of a rivet 63, a resilient metal member or leaf spring 64.

The free end portion of spring 64 is initially bent to extend inwardly at such an angle as to engage one end of the lower pivot pin 39 (Fig. 5) under a predetermined degree of compression or strain, whereby spring 64 acts to normally bias lever 61 to the full line position thereof illustrated in Fig. 5. As a result the end portion 61^b of lever 61 is positioned with an edge portion 61^c underlying the flat lower surface of the upper pushbutton 36. However, the edge portion 61^c is angled downwardly to form a cam surface, so that upon depression of said upper pushbutton 36 the peripheral lower edge of the latter engages the cam surface 61^c to force lever 61 to rotate in a counterclockwise direction to the dotted line position thereof (Fig. 5) against the bias of spring 64. Consequently the flat upper edge 61^d of end portion 61^a is positioned directly beneath the flat under surface of the lower pushbutton 36 (Fig. 5) to positively prevent depression of the latter. Upon manual release of the upper pushbutton 36, spring 64 acts to automatically return lever 61 to the full line position thereof shown in Fig. 5.

Conversely, if the lower pushbutton 36 is first depressed (Fig. 5) to effect circuit-completing operation of its associated switch mechanism said pushbutton will be positioned in a relation to positively prevent counterclockwise rotation of interlocking lever 61, wherefore the inclined or cam edge 61^c of the portion 61^b thereof will cooperate with the lower surface of the upper pushbutton 36 to positively prevent a substantial degree of depression of the latter, thus preventing circuit-completing operation of the switch parts associated therewith. As best illustrated in Figs. 5 and 7, the lever 61 is preferably cut away at 61^e to provide proper clearance between the same and the boss 50^a forming a part of the metal top plate of the upper switch 50.

The left-hand switch (Fig. 4) is provided with four, and the right-hand switch is provided with two, bottom-wiring terminal members 65, the relatively long substantially vertical arms of said terminal members being preferably bent to the form thereof illustrated in dotted lines at 65^a at the right-hand end of Fig. 4. Members 65 when formed as shown conform very closely to the contour of the outer surfaces of the end walls of the molded insulating bases of switches 50, thus providing a more rigid support for such members, improving the appearance of the switches, and affording a maximum utility of the integral insulating barriers between the terminal members at opposite ends of the respective switch bosses.

The horizontal portions of terminal members

65 are tapped to receive the shanks of binding screws 66, which in practice are substantially larger than the binding screws 45 of Figs. 1 to 3. Members 65 are secured in position by screws 67, which are preferably formed of steel and are of substantially larger size than the screws 44 of Figs. 1 to 3. Screws 67 may, of course, be provided with lock-washers (not shown) to prevent accidental loosening thereof. The two inner end 10 terminal members of the right-hand switch of Fig. 4, one of which members is shown at 68, are of relatively thinner stock than terminal members 65. The arms of members 68 are of substantially equal length and are bent at a right 15 angle to each other, the vertical arm of each having an opening to provide clearance for the shank of its associated securing screw 67, and the horizontal arm of each having an opening to provide clearance for the shank of its associated binding screw 66.

The grounding terminal screw 49 is arranged in substantially the same manner described in connection with Figs. 1 to 3. The casing sections may, if desired, be ornamented in the manner disclosed in my aforementioned Design Patent No. 121,962. The section or cover 52 of the casing is secured to section 51 as by means of four screws, two of which are shown at 69 in Fig. 6, in the manner described in connection with 25 Figs. 1 to 3. The elements not specifically described in connection with the device of Figs. 4 to 7 function in the same manner as set forth in the description of Figs. 1 to 3.

In the modified form of pendant pushbutton 35 station illustrated in Figs. 8 to 12 I employ a pair of slow-make, slow-break switches 70, 70 of the character disclosed and claimed in Patent No. 2,133,545, granted October 18, 1938, to A. W. Krieger. The switches shown (full size) in Figs. 40 8 to 12 are particularly adapted for control of alternating current circuits, for reasons set forth in said Patent No. 2,133,545, said switches having a rating of 15 amperes at 250 volts alternating current. The switches 70 of Figs. 8 to 12, 45 which are of the three-pole type, differ in respect of certain structural details from the three-pole switch shown in Figs. 17 to 19 of said Patent No. 2,133,545.

More particularly, the disk or cylinder 71 (Figs. 50 8 to 10 hereof) is rotatably supported by a pin 72, which is in turn rotatably supported by the insulating plunger 73, the length of pin 72 and the form of plunger 73 being such that accidental lateral disassembly of said pin from disk 55 71 is positively prevented (see Fig. 10). Similarly the pairs of stationary contacts 74, 74 and the contactors 75 (see Fig. 8) have silver tips or buttons attached thereto, as by spot welding, as distinguished from the "inlaid" form of contact 60 tips specifically disclosed in Patent No. 2,133,545. Moreover, each switch 70 is normally biased to its circuit interrupting position, as by means of a coiled compression spring 76, one end of which 65 surrounds an extrusion or boss 77 formed upon a plate 78 which seats against an end wall of a recess formed in the upper section 79 of the insulating casing of the switch, the other end of spring 76 surrounding the end 80 and bearing against the shoulders 81 formed upon a composite metal yoke member, the spaced arm portions 82 and 83 of which (Figs. 8 and 12) have their ends notched to provide an open pivotal connection thereof with the opposite ends of a pin 84 which is rigidly attached to the switch 70 lever 85, whereby the latter is normally biased

to the position thereof illustrated at the right-hand end of Fig. 8.

The structural details of the switches 70, including the details just mentioned, form no part of the present invention; and it is to be understood that other suitable forms of slow-make, slow-break switches may be utilized, provided that the same are so constructed as to normally effect operation of the parts thereof to circuit interrupting position.

The lever 85 of each switch 70 is pivotally supported by a pin 86 substantially in the manner of the toggle lever (56, Fig. 19) of Patent No. 2,133,545. As will be noted, however, the levers 85 are of special form, each comprising an arm 87 the perforated end of which is positioned within a kerf 88 in the lower end of the reduced portion 89 of a pushbutton 90. Said reduced portion 89 is provided with openings alined with each other and with the perforation in arm 87, a headed pin 91 having its shank extended through said openings and said perforation to provide a pivotal connection between each button 90 and its associated lever 85, the shank of said pin having its end upset, as indicated at 91a in Fig. 10, to permanently secure said parts in assembled relation.

Each lever 85 is also provided with an arm 92 having a hooked end 93 which penetrates alined openings in the metal supporting plate 94 (which is common to the two switches) and in the insulating top plate 95 (see Fig. 8) whereby the portion 96 of arm 92 is adapted to engage the upper surface of plate 94, to limit the degree of clockwise rotation of lever 85 (and consequently the degree of upward displacement of the pushbutton 90 associated therewith) under the bias of spring 76. Under these conditions cam portion 97 of lever 85 acts upon cylinder 71 to depress plunger 73 and the contactors 75 to effect 40 circuit interruption.

Upon depression of either pushbutton 90 (as shown in dotted lines at the left-hand side of Fig. 8) the lever 85 associated therewith is rotated counterclockwise, so that its cam portion 97 acts to permit upward movement of cylinder 71 and the plunger 73 and contactors 75 associated therewith, under the bias of springs 98, thus completing the circuit controlled by that particular switch.

Each switch 70 is provided with six bottom wiring terminal elements, the binding screws of which are designated by the numerals 99 (Fig. 8). In accordance with my invention the longitudinally adjacent terminals of the two switches are electrically connected, as by means of three flat bus members or conductor plates, one of which is shown at 100 in Fig. 8. The bus members 100 are perforated at opposite ends thereof to accommodate the shanks of the intermediate binding screws 99, whereby the bus members are clamped in assembled position by the heads of said binding screws. As will be apparent, only one of the two screws associated with each bus member is utilized for attachment of the circuit wire common thereto.

Supporting plate 94 is preferably of the form best illustrated in Fig. 9, the same having two pairs of tapped openings, diagonally spaced from each other, to accommodate the shanks of bolts 101 by which the assembled switches are attached thereto. Plate 94 is provided with four symmetrically arranged openings 94a, 94b, 94c and 94d to accommodate the shanks of screws (not shown) whereby plate 94 may be secured

to the relatively larger section 102 of the metal enclosing casing, the relatively smaller section (not shown) having a recess of sufficient depth to provide ample clearance for the insulating bases of switches 70, and the same being attachable to section 102 as by means of four screws or bolts, as described in connection with the other switching devices.

As shown in Fig. 8, the circular walls of openings 102a and 102b are made of substantial depth or thickness to insure substantially straight-line reciprocating movements of pushbuttons 90 with respect thereto. Also, as indicated by the dotted line illustration at the left-hand side of Fig. 8, the edge portion 92a of arm 92 is adapted to abut against the periphery of the pushbutton 90 associated therewith upon a given degree of depression of the latter, to thereby positively limit the degree of depression of the pushbutton and the degree of counterclockwise rotation of its associated lever 85. By the means aforescribed proper operation of the parts of the switches individually is insured.

As in the forms of my invention heretofore described, it is necessary or desirable to insure against simultaneous completion of the circuits controlled by the two switches 70. Accordingly I provide a mechanical interlocking connection between the two pushbuttons 90, which connection is preferably in the form of a teetering bar or lever 103 of the character best illustrated in Fig. 11. Thus lever 103 consists of a one-piece punched and stamped sheet metal member having arms 103a and 103b extending upwardly at a predetermined relatively wide angle with respect to each other. In practice the arms 103a and 103b are united throughout their length by struts 103c and 103d produced from the one-piece blank by the stamping operation, thus insuring substantial rigidity or unyielding relationship of arms 103a and 103b with respect to each other.

Arms 103a, 103b are cut away or notched at 103e and 103f to provide clearance between the same and the reduced portions 89 of pushbuttons 90, whereby the outer ends of said arms will respectively underlie the central portions of said pushbuttons. As shown in dotted lines in Fig. 8, member 103 is so arranged with respect to pushbuttons 90 that upon substantially full depression of either of the latter the arm 103a or 103b associated therewith is likewise depressed to a position parallel with and closely adjacent to the upper surface of plate 94, under which condition the other arm 103b or 103a, as the case may be, is tilted upwardly to positively engage and restrain depression of the other pushbutton.

In order to retain member 103 in assembled relationship to the other parts without rattling, and to normally yieldably hold the two pushbuttons 90 in their upper extreme positions, to prevent possible rattling at the pivotal connections 91 (Fig. 8) I provide a pair of leaf springs 104, composed of phosphor bronze or other resilient metal, the ends 104a, 104b of said springs being positioned flatwise upon the upper surface of plate 94 and rigidly secured or fixed thereto, as by spot-welding. The main body portions of springs 104 are bent or angled upwardly, as shown at the left-hand end of Fig. 8 to normally respectively yieldably engage the under surfaces of the arms 103a and 103b of member 103, whereby the latter is held in the position thereof illustrated in full lines in Fig. 8. As shown, the arm 103a is provided with a slot or opening 103g to provide clearance for the arm 92 and hooked end

§3 of the lever 85 associated with the left-hand switch in Fig. 8.

As illustrated in Figs. 8 and 9, plate 94 is provided with lugs 94^e, 94^f, 94^g and 94^h partially sheared and bent downwardly therefrom for engagement with vertical end grooves in the upper sections 79, 79 of the switch bases, to assist in restraining lateral movement thereof with respect to plate 94. A grounding terminal screw 105, of the character described in connection with the other devices, is also preferably provided. As illustrated in Fig. 10, plate 94 is preferably provided with pairs of downward extrusions or bosses 94ⁱ and 94^j which penetrate corresponding pairs of openings in the respective insulating cover plates 95 and bear against the respective pivot pins 86 to more firmly retain the latter in the bearings or seats provided therefor in the top surfaces of the upper insulating sections 79 of the switch casings. As afore-indicated, the switching device of Figs. 8 to 12 is likewise adapted to serve as a pendant pushbutton station for reversing control of a hoist motor or the like.

What I claim as new and desire to secure by Letters Patent is:

1. In a pendant pushbutton control station for hoist motors and the like, in combination, a metal casing divided longitudinally in a plane parallel to the front face thereof, said front face of the casing having a pair of openings formed therein, a pair of structurally complete electric switch units of like form, a metal supporting member to which each of said switch units is rigidly secured, said supporting member being in turn secured to the front section of said casing, each of said switch units having a separately molded insulating base, a plurality of sets of stationary and movable contacts carried by each base, a switch operating lever pivotally supported relatively to each base, a single pushbutton element pivotally connected with each lever at a point offset from the point of pivotal support of the latter and extending through one of said casing openings, and mechanical interlocking means comprising a sheet metal member oscillatably attached to said supporting member and associated with said pushbutton elements to positively insure against simultaneous depression of the pushbuttons to degrees sufficient to effect operation of the switch mechanisms associated therewith, while providing for depression of either of said pushbuttons singly, each of said levers having spring means individual thereto to normally bias the same and its associated pushbutton in a direction to effect circuit interrupting operation of the respective switch mechanism.

2. In a pushbutton control station, in combination, a manually operable switch assembly comprising, a metal member, a pair of multi-pole switches of like form secured to the lower surface of said metal member, each of said switches having a single pivoted operating lever extending upwardly beyond said metal member, a pair of pushbuttons each pivotally connected with one of the respective levers in offset relation to the point of pivotal support of the latter, spring means associated with the respective levers to normally bias each of the same to a given extreme position forwardly of the front surface of said metal member to provide for "off" positioning of its associated switch mechanism, means including said levers cooperatively associated with said pushbuttons to positively pre-

vent simultaneous depression thereof to their inner extreme positions, for the purpose set forth, and means comprising a cover member to which said metal member is rigidly attached, said cover member having openings to accommodate said pushbuttons and to assist in restricting each of the same to reciprocating movements in a substantially straight line.

3. In a pendant pushbutton control station for hoist motors and the like, in combination, a metal casing divided longitudinally in a plane parallel to the front face thereof, a pair of electric switches of like construction rigidly secured to the front section of said casing, each of said switches having a separately molded insulating base, a plurality of sets of stationary and movable contacts carried by each base, a single pushbutton operating element associated with each base and extending therefrom through said front face of the casing, each of said operating elements including a lever pivotally supported relatively to the base, mechanical interlocking means comprising an oscillatably supported sheet metal member associated with said pushbutton operating elements to positively insure against simultaneous depression of the pushbuttons to degrees sufficient to effect operation of the switch mechanisms associated therewith, while providing for depression of either of said pushbuttons singly, for the purpose set forth, a coiled compression spring associated with each lever to bias the respective pushbutton out of its depressed position, and said switches having wiring terminal elements exposed at the rear thereof to facilitate wiring of said switches after the latter are secured to said front section of the casing.

4. In a switch mechanism for reversing control of hoist motors and the like, in combination, a hollow cast metal enclosing casing divided longitudinally to provide a front section of relatively great depth and a rear section of relatively small depth, said front section having a plurality of recessed and tapped posts formed integrally with the opposite side walls thereof and offset inwardly a substantial distance from the open end thereof, a flat sheet metal plate having openings aligned with the recesses in said posts, a pair of electric switches of like construction rigidly attached to said plate in tandem relationship to each other, the insulating base portions of said switches being positioned at the rear face of said plate and the operating elements thereof being positioned forwardly of the front face of said plate, the operating elements of the respective switches each comprising a switch operating lever pivotally supported in a substantially central relation to the switch base and a single pushbutton pivotally connected with said lever in longitudinally offset relation to the center of the switch base, the front wall of said casing having openings to provide sliding clearance for the pushbuttons and to assist in guiding the latter, each of said pushbuttons having means associated therewith to bias the same to its outer extreme position, mechanical interlocking means to insure against simultaneous depression of said pushbuttons to their respective inner extreme positions, and a plurality of screws penetrating said plate openings and engaging said tapped recesses to secure said plate and said switches to said front section of the casing.

5. In a switch mechanism for reversing control of hoist motors and the like, in combination, a hollow cast metal enclosing casing divided longitudinally to provide a front section of relatively

great depth and a rear section of relatively small depth, said front section having a plurality of recessed and tapped posts formed integrally with the opposite side walls thereof and offset inwardly a substantial distance from the open end thereof, a flat sheet metal plate having openings alined with the recesses in said posts, a pair of electric switches of like construction rigidly attached to said plate in tandem relationship to each other, the insulating base portions of said switches being positioned at the rear face of said plate and the operating elements thereof being positioned forwardly of the front face of said plate, the operating elements of the respective switches each comprising a switch operating lever pivotally supported in a substantially central relation to the switch base and a single pushbutton pivotally connected with said lever in longitudinally offset relation to the center of the switch base, the front wall of said casing having openings to provide sliding clearance for the pushbuttons and to assist in guiding the latter, each of said pushbuttons having means associated therewith to bias the same to its outer extreme position, mechanical interlocking means to insure against simultaneous depression of said pushbuttons to their respective inner extreme positions, a plurality of screws penetrating said plate openings and engaging said tapped recesses to secure said plate and said switches to said front section of the casing, each of said pushbuttons having an inverted channel-shaped metal member rigidly attached thereto and adapted to limit the degree of outward movement thereof, and said front section of the casing having pairs of transversely spaced ribs formed integrally therewith and cooperating with said inverted channel-shaped members to restrain said pushbuttons against rotary movement and to assist in limiting the same to reciprocating movement in a straight line.

6. As an article of manufacture, a hollow switch casing comprising two cast metal sections, the front section being relatively deep and the rear section being relatively shallow, said front section having a pair of longitudinally spaced openings formed in the front wall thereof to provide slideable clearance for pushbutton operating elements of suitable form, said front section having a plurality of recessed and tapped posts formed integrally with the opposite side walls thereof and offset inwardly from the open end thereof to provide a ledge for attachment of a multiple switch supporting plate of suitable form, said front section also having a plurality of recessed and tapped posts formed integrally with the opposite side walls thereof and arranged in a substantially flush relation to said open end, the rear section of said casing having openings alined with said posts last mentioned to provide clearance for the shanks of screws employed to releasably secure the casing sections in assembled relation, said front section having pairs of transversely spaced ribs formed on the opposite side walls thereof and offset inwardly from the plane of the ledge formed by said posts first mentioned, and each pair of ribs being adapted to cooperate with an element of a pushbutton to restrain the latter against rotary movement and to assist in limiting the latter to reciprocating movement in a straight line.

7. As an article of manufacture, a manually operable reversing switch assembly of the pushbutton type comprising, a relatively long, flat sheet metal plate having a pair of longitudinally

spaced openings formed therein, a pair of multi-pole switches of like form secured to said plate in tandem relationship to each other, said switches having insulating base portions arranged at the rear face of said plate and pivotally supported operating levers extending upwardly through said plate openings and having portions thereof exposed at the front face of said plate, a pushbutton pivotally connected with each lever in longitudinally offset relation to the point of pivotal support of the latter, spring means associated with each pushbutton to normally bias the same to a given extreme position forwardly of the front face of said plate, and means cooperatively associated with said pushbuttons to positively prevent simultaneous depression thereof to their inner extreme positions, for the purpose set forth.

8. As an article of manufacture, a manually operable reversing switch assembly of the pushbutton type comprising, a relatively long flat sheet metal plate having a pair of longitudinally spaced openings formed therein, a pair of multi-pole switches of like form secured to said plate in tandem relationship to each other, said switches having insulating base portions arranged at the rear face of said plate and pivotally supported operating levers extending upwardly through the respective plate openings and having portions thereof exposed at the front face of said plate, a pushbutton pivotally connected with each lever in longitudinally offset relation to the point of pivotal support of the latter, spring means individual to each pushbutton to normally bias the same to its extreme position forwardly of the front face of said plate, and means including an arm formed integrally with one of the switch levers and an element associated with the pushbutton of the other switch to insure against simultaneous depression of the pushbuttons to their inner extreme positions respectively, for the purpose set forth.

9. As an article of manufacture, a manually operable reversing switch assembly of the pushbutton type comprising, a relatively long, flat sheet metal plate having a pair of longitudinally spaced substantially circular openings formed therein, a pair of double-pole, two-position, snap switches of like form secured to said plate in tandem relationship to each other, said switches having insulating base portions arranged at the rear face of said plate and pivotally supported operating levers extending upwardly through said plate openings and having portions thereof exposed at the front face of said plate, a pushbutton pivotally connected with each lever in longitudinally offset relation to the point of pivotal support of the latter, said switches being of the spring toggle type whereby the same are normally biased individually to either the "on" or the "off" position thereof depending upon the positions of their respective levers, overpowering spring means associated with each pushbutton to normally bias the same and its associated lever to a given extreme position to provide for "off" positioning of its respective switch, each of said pushbuttons being normally adapted upon depression thereof to its inner extreme position to provide for operation of its associated switch to "on" position, and means for mechanically interlocking said pushbuttons to positively prevent simultaneous depression thereof to their inner extreme positions.

10. As an article of manufacture, a manually operable reversing switch assembly of the push-

button type comprising, a relatively long, flat sheet metal plate having a pair of longitudinally spaced substantially circular openings formed therein, a pair of double-pole, two-position, snap switches of like form secured to said plate in tandem relationship to each other, said switches having insulating base portions arranged at the rear face of said plate and pivotally supported operating levers extending upwardly through said plate openings and having portions thereof exposed at the front face of said plate, a pushbutton pivotally connected with each lever in longitudinally offset relation to the point of pivotal support of the latter, said switches being of the spring toggle type whereby the same are normally biased individually to either the "on" or the "off" position thereof depending upon the positions of their respective levers, overpowering spring means associated with each pushbutton to normally bias the same and its associated lever to a given extreme position to provide for "off" positioning of its respective switch, each of said pushbuttons being normally adapted upon depression thereof to its inner extreme position to provide for operation of its associated switch to "on" position, means comprising a metal lever pivotally supported by said plate for oscillatory movement in a plane parallel thereto, said metal lever having an arm upstanding from each end thereof, spring means for biasing said lever to a given extreme position wherein one arm thereof underlies one of said pushbuttons, said last mentioned arm having a cam surface engageable by said last mentioned pushbutton to oscillate said lever against the bias of said spring means into underlying relation to the other pushbutton when the latter is in its upper extreme position, said lever arms thus acting to permit depression of one or the other of said pushbuttons while positively preventing simultaneous depression of both pushbuttons to their inner extreme positions.

11. In combination, a relatively long, flat sheet metal plate having a pair of longitudinally spaced substantially circular openings formed therein, a pair of double-pole, two-position, snap switches of like form secured to said plate in tandem relationship to each other, said switches having insulating base portions arranged at the rear face of said plate and pivotally supported operating levers extending upwardly through said plate openings and having portions thereof exposed at the front face of said plate, a pushbutton pivotally connected with each lever in longitudinally offset relation to the point of pivotal support of the latter, said switches being of the spring toggle type whereby the same are normally biased individually to either the "on" or the "off" position thereof depending upon the positions of their respective levers, overpowering spring means associated with each pushbutton to normally bias the same and its associated lever to a given extreme position to provide for "off" positioning of its respective switch, each of

said pushbuttons being normally adapted upon manual depression thereof to its inner extreme position to provide for operation of its associated switch to "on" position, means for mechanically interlocking said pushbuttons to positively prevent simultaneous depression thereof to their inner extreme positions, means comprising a longitudinally divided metal casing providing an enclosure for said pair of switches, said casing having a pair of openings in one face thereof through which said pushbuttons project, and said casing having an opening in an end thereof to provide for entrance of a cable or conductor, said cable being adapted to suspend said casing and the switches carried by the latter.

12. A pushbutton reversing control station for hoist motors and the like, comprising, in combination, a relatively long, flat sheet metal plate having a pair of longitudinally spaced openings formed therein, a pair of multi-pole switches of like form secured to said plate in tandem relationship to each other, said switches having insulating base portions arranged at the rear face of said plate and pivotally supported operating levers extending upwardly through said plate openings and having portions thereof exposed at the front face of said plate, a pushbutton pivotally connected with each lever in longitudinally offset relation to the point of pivotal support of the latter, spring means associated with each pushbutton to normally bias the same to a given extreme position forwardly of the front face of said plate, means cooperatively associated with said pushbuttons to positively prevent simultaneous depression thereof to their inner extreme positions, said switches having a plurality of bottom-wiring terminal members positioned at each end of the respective insulating base portions thereof, and means for electrically connecting the longitudinally adjacent pairs of terminal members at the adjacent ends of said insulating base portions, said means including means for detachably connecting circuit wires respectively common to said adjacent pairs of terminal members.

13. As an article of manufacture, a manually operable switch assembly of the pushbutton type comprising, a relatively long, flat sheet metal plate, a pair of multi-pole switches of like form secured to said plate, said switches having pivoted operating levers extending upwardly beyond said plate, a pushbutton pivotally connected with each lever in offset relation to the point of pivotal support of the latter, spring means associated with each pushbutton to normally bias the same to a given extreme position forwardly of the front face of said plate, and means cooperatively associated with said pushbuttons to positively prevent simultaneous depression thereof to their inner extreme positions, for the purpose set forth.

GEORGE J. MEUER.
